UNITED STATES PATENT OFFICE.

JERROLD F. WALTON, OF STURGIS, MICHIGAN.

CHAIR-BACK.

1,254,949.

Specification of Letters Patent. Patented Jan. 29, 1918.

Application filed April 26, 1915. Serial No. 23,834.

To all whom it may concern:

Be it known that I, JERROLD F. WALTON, a citizen of the United States, residing at Sturgis, Michigan, have invented certain new and useful Improvements in Chair-Backs, of which the following is a specification.

This invention relates to improvements in chair backs, and particularly to improved means for securing the depending controlling arm for hinged chair backs.

This invention relates to the structure appearing in Letters Patent No. 1,137,246, issued April 27, 1915, and shows an improved and modified means for securing the arm in position on the back.

The object of my invention is to provide an improved attaching means for such an adjusting arm. Objects relating to details and economies of construction and operation will definitely appear from the detailed description to follow.

I accomplish the objects of my invention by the devices and means described in the following specification. The invention is clearly defined and pointed out in the claims.

A structure constituting a preferred embodiment of my invention is clearly illustrated in the accompanying drawing, forming a part of this specification, in which:

Figure I is a detail perspective view of the lower portion of a hinged chair back, portions being cut away to show details.

Fig. II is an enlarged detail sectional view on line 2—2 of Fig. I, showing details of the construction of the rod and of the supporting means therefor.

Fig. III is a detail view showing the manner of striking out the supporting lugs 11, 11 on the surface of the rod.

Fig. IV is an enlarged detail view of the blank from which the bottom supporting clip on the chair back is made.

Fig. V is a detail perspective view of a modified form of construction.

Fig. VI is a detail transverse view showing the insertion of a pin 16 through the arm 4 for securing the same result as the struck-up lugs 11, 11.

In the drawing the sectional views are taken looking in the direction of the little arrows at the ends of the section lines and similar numerals of reference refer to similar parts throughout the several views.

Considering the numbered parts of the drawing, the chair back is made up of side

bars 1, 1 and a bottom cross bar 2 and cross bars 3, 3 above the same. Secured to the cross bars is a vertical arm 4 having a straight round shank. On the under side 60 of the bottom bar 2 is secured a clip 5 by suitable screws 6 said clip having a hole 7 therethrough with a lateral slot 8 at each side and having a folded over upper portion 9 with a round hole 10, the portion 9 being folded back parallel with the body of the plate and the hole 10 registering with the hole 7. Lugs 11, 11 are struck out on the sides of the arm 4 so that when the arm is inserted up through the clip 5 the lugs pass 65 up through the slots 8, 8 and when the rod is turned a quarter turn the same is locked in position so that it can be neither raised nor lowered. Clip pieces 12, 12 are secured to the under side of the bars 3, 3 and contain 70 the round holes 13, 13 through which the upper end of the arm 4 extends whereby said clip pieces serve as securing means for attaching the arm to the chair back. A round rod is preferred, but similar results can be 75 attained by other forms. In the modified structure shown in Fig. V, the upper clip 14 is provided with an angular arm 15 which extends over the perforation and constitutes a stop for the arm 4, and the lower clip 5' merely comprises a flat plate provided with 80 a hole and slots like the hole 7 and slots 8 of Fig. IV. In this modification a pin 16 is arranged through the rod to project at each end, the projecting ends performing the 85 functions of the lugs 11, 11.

It will thus be seen that by providing sheet metal clips which can be secured in place by screws and projecting slightly at the back of the chair, a structure which can 95 be very readily assembled and disassembled by hand alone is provided, so that the chair with this feature can be very readily taken apart and shipped in the knock down, the same as the chair of my said Letters Patent. 100 This structure is available with light cross bars or slats. It can be modified to a considerable extent without departing from my invention, as pointed out in the appended claims.

Having thus described my invention, what I claim as new and desire to secure by Letters Patent, is:

1. The combination of an adjustable back, a detachable arm with a round straight 110 shank part, clip members secured to the said back, having holes in line to receive the said

arm, the bottom one of which has a slotted hole and a portion folded over with a round hole registering with the bottom hole, a projection on said arm adapted to pass the slots 5 to coact with the said clip to retain the arm in position, as specified.

2. In a chair, the combination with a hinged back, having side bars and cross bars, sheet metal clip pieces secured to the under 10 side of said cross bars and projecting therefrom and containing perforations, the bottom of which contains a perforation with lateral notches, an arm with projections disposed in said perforations and adapted to engage the lower plate and be supported thereby, and a stop means for preventing the 15 upward movement of said bar.

3. In a chair, the combination with a hinged back, having side bars and cross bars, 20 clip pieces secured to the under side of said cross bars and projecting therefrom and con-

taining perforations, the bottom of which contains a perforation with lateral notches, and an arm with projections disposed in said perforations and adapted to engage the 25 lower plate and be supported thereby.

4. In a chair, the combination with a hinged back comprising side bars and cross bars; clip pieces secured to the crossbars and projecting therefrom and containing perforations, an arm disposed in said perforations, and projections on said arm coacting with one of the plates whereby the arm is supported longitudinally.

In witness whereof, I have hereunto set 35 my hand and seal in the presence of two witnesses.

JERROLD F. WALTON. [L.S.]

Witnesses:

F. T. SMITH,
ALVENA K. SCHAFER.
